ATTORNEY.

UNITED STATES PATENT OFFICE

CHARLES LINDNER, OF CARLINVILLE, ILLINOIS.

TOILET-BRACKET.

SPECIFICATION forming part of Letters Patent No. 295,567, dated March 25, 1884.

Application filed June 18, 1883. (No model.)

To all whom it may concern:

Be it known that I, CHARLES LINDNER, a citizen of the United States, residing at Carlinville, in the county of Macoupin and State of Illinois, have invented certain new and useful Improvements in Toilet-Brackets, of which the following is a specification, reference being had therein to the accompanying drawings.

This invention relates to improvements in portable toilet or dressing cases, and the object thereof is to provide a receptacle divided off by a partition, said partition serving as a shelf for toilet-articles, with a looking-glass pivoted or journaled in the sides of the case, whereby said glass may be swung in any position desired, and also serve as a lid or cover to close the case when not in use; and the invention consists in the novel construction and arrangement of parts, as will be hereinafter more fully described and specifically claimed.

In the annexed drawings, to which reference is made, and which fully illustrate my invention, Figure 1 is a vertical sectional view of my device, and Fig. 2 is a front view of the same.

A represents the back part of a quadrilateral case, said back being made in the form of a shield and provided with one or more holes, a, therein, by which it—that is, the case—may be suspended to the wall or any convenient place. B is the top thereof.

C C are sides, in which the ends of a shelf, D, are secured in any suitable manner.

E is a looking-glass, also of quadrilateral form, which is journaled or pivoted in the sides of the case just a little below the line of the shelf, so that it may be swung in any desired position required.

F is an angular bottom, within which articles of any kind to be used are placed also, and are made secure from view by means of the glass when it is in its normal or proper position.

G G are two small bracket-shelves, secured to the back and sides of the case outside of the receptacle portion of said case, which may be used for placing ornaments of any kind thereon.

In using my case it will only be necessary for the person so using to hang it upon nails or screws driven into the wall or mantel, whichever may be most convenient, and what articles that may be necessary to use after the glass has been swung down at right angles to the case (said glass forming a lid or cover) are then taken out for use, and the glass is then swung back again to its normal position, and can then be changed to any desired position and used as a looking-glass. It will be seen that the glass has a twofold purpose—*i. e.*, it can be used as a looking-glass and a lid or cover for the receptacle.

This case can be conveniently carried around by persons traveling, and hung up in their rooms—a great desideratum, if none should be found already there—and in its construction it is durable and cheap to manufacture.

What I claim, and desire to secure by Letters Patent, is—

In a toilet-bracket case, the combination of the case A, horizontal shelf D, bracket-shelves G G, and pivoted glass E, substantially as described, whereby the glass is raised to a vertical position or dropped to a horizontal position to open and close the case, all constructed, arranged, and operating as and for the purposes set forth.

In testimony whereof I affix my signature in presence of two witnesses.

CHARLES LINDNER.
